(57) **CLAIM**

The ornamental design for an anemometer mount as shown and described.

DESCRIPTION

FIG. 1 is a front elevational view of an anemometer mount according to my new design;
FIG. 2 is a right side elevational view of the anemometer mount of FIG. 1;
FIG. 3 is a left side elevational view of the anemometer mount of FIG. 1;
FIG. 4 is a rear elevational view of the anemometer mount of FIG. 1;
FIG. 5 is a top plan view of the anemometer mount of FIG. 1;
FIG. 6 is a bottom plan view of the anemometer mount of FIG. 1;
FIG. 7 is a perspective view of the anemometer mount of FIG. 1; and,
FIG. 8 is a perspective view of the anemometer mount of FIG. 1 from an opposite side of the anemometer mount as shown in FIG. 7.
The broken line showing in the drawings is for illustrative purposes only and forms no part of the claimed design.
